CLAIM

The ornamental design for illuminated plant pot, as shown and described.

DESCRIPTION

FIG. 1 is a top plan view of a illuminated plant pot showing my new design;

FIG. 2 is a front elevational view thereof;

FIG. 3 is a bottom plan view thereof;

FIG. 4 is a left side elevational view thereof;

FIG. 5 is a back view thereof;

FIG. 6 is a right side elevational view thereof; and,

FIG. 7 is an exploded view showing the parts of my design, the broken line showing of the plant is for illustrative purposes only and forms no part of the claimed.
